United States Patent Office

Des. 195,782
Patented July 30, 1963

195,782

TEMPLATE

John M. Drinkwater, 45 Marble Hill Ave., Bronx, N.Y., and Norman Blau, 141 E. 33rd St., New York, N.Y.

Filed Dec. 31, 1962, Ser. No. 72,996

Term of patent 14 years

(Cl. D52—6)

FIG. 1

The rear of the template is a mirror image of the top.
We claim:

The ornamental design for a template, substantially as shown and described.
